UNITED STATES PATENT OFFICE.

EDWARD GIBSON, OF JERSEY CITY, NEW JERSEY.

DUMPING-GRAVE FOR FURNACES.

1,116,409.

Specification of Letters Patent.

Patented Nov. 10, 1914.

Application filed January 21, 1914. Serial No. 813,391.

To all whom it may concern:

Be it known that I, EDWARD GIBSON, a citizen of the United States, residing in Jersey City, county of Hudson, in the State of New Jersey, iron-founder, have invented a certain new and useful Improvement in Dumping-Grates for Furnaces; and I do hereby declare that the following is a full and exact description thereof.

10 I maintain the much approved style of dumping grates made in sections with the proper liberal air spaces, removably mounted on a rocking shaft, the dumping being effected when required by tilting the whole 15 on trunnions formed on the rocker and supported on suitable stationary bearings. The sections are rectangular, mounted side by side and capable of being separately removed by simply lifting when liberated.

20 The sections are relatively long and narrow and have a longitudinal flange on each edge deeply notched to receive the rocker. Each has another strengthening part which I will term the central rib extending along 25 the middle. This latter is not notched or otherwise contracted but contributes its full depth to strengthen the section.

The rocker is formed with a deep notch on its upper edge and great deepening of 30 the body to accommodate such rib without weakening as it extends past the rocker. I have discovered that the work may be greatly further strengthened, and the change made also a means for locking the sections 35 to the rocker as has been long practised with other styles of grates so that the sections will never be shaken out of engagement by the most energetic dumping motions. The construction also allows an increase in the depth 40 of the jaws by which the sections engage the rocker.

The following is a description of what I consider the best means of carrying out the invention.

45 It will be understood that the sections may be in a greater or less number.

The accompanying drawings form part of this specification.

Figure 1, is a longitudinal section of my 50 furnace with four sets of sections, and four rockers. Fig. 2 shows a rocker with one section in position for work. Fig. 3 is a plan view of a portion of a furnace with a part broken away, showing horizontal section 55 there. Fig. 4 is a section on the line 4—4 in Fig. 3. Fig. 5 is a perspective view showing

one section detached and inverted. Fig. 6 is a perspective view showing the rocker detached.

Similar letters of reference indicate corresponding parts wherever they appear.

Referring to the drawing and the marks of reference thereon, A indicates the ordinary frame of cast iron with the usual bearings for the trunnions. The other parts differ a little from the ordinary.

B is a rocker, B¹ the trunnions and b a deep notch for the central ribs of the corresponding sections, and b¹ are holes to be described below, each ready to receive a locking pin.

D is a section, D¹ D² the edge flanges, each of the latter having its proper deep notch to receive and match closely to the rocker when the parts are applied together, compelling the section to conform to the tilting motions of the rocker.

D³ and D⁴ are transverse braces extending across the entire section, cast integral with the central rib and with the side flanges and strengthening the whole. Holes "d" are cored or otherwise formed in these braces which match in size and position to the holes "b¹" in the rocker B which is closely adjacent. E E¹ are pins of steel or other 85 strong and refractory material extending through the slightly larger holes and holding the rocker and the sections reliably together. The holes are countersunk at each end to facilitate the introduction of a pin 90 when the parts are more or less out of position. One end of each pin is formed with a bend "E¹" which may serve with any ordinary appliance, either alone or in combination with a gentle pressure or slight blow on 95 the other end, to remove any pin when it is required to unlock.

As with most styles of grates the sections are short-lived. They fail at unequal periods. My construction prolongs the life 100 of these important and severely burned irons by making flanges and rib mutually support each other by the cross braces "D³", and the pins "E E¹" provide against the section being thrown off.

Modifications may be made without departing from the principle or sacrificing the advantages of the invention. The proportions may be changed within wide limits. Parts may be used without the whole. One 110 or both the locking pins "E E¹" may be omitted. Both may be sometimes omitted in

practice where it is believed for any reason that the risk of throwing out a section is very slight. One pin is sufficient in any ordinary cases but I propose to provide 5 always four of the holes in the braces D³ and two of the holes in the rocker B, as shown. The pins are interchangeable.

I claim as my invention:

1. The grate described comprising rockers, 10 having notches, and removable fuel supporting sections, each having a centrally disposed, continuous, longitudinal rib, adapted to match in one of said notches and to reinforce said section, flanges notched to receive 15 said rockers, and reinforcing centrally disposed, transverse braces, cast with said sections.

2. The grate described comprising rockers, having notches, and removable fuel supporting sections, each having a centrally disposed, continuous, longitudinal rib, adapted 20 to match in one of said notches and to reinforce said section, flanges notched to receive said rockers, reinforcing centrally disposed, transverse braces, cast with said sections, 25 and removable means extended through said braces and rockers and locking said parts.

Signed at New York city this 16 day of January 1914.

EDWARD GIBSON.
